UNITED STATES PATENT OFFICE.

JULIUS GUTMANN, OF BERLIN, GERMANY, AND EMIL FALLER AND KARL MISCHKE, OF ZURICH, SWITZERLAND, ASSIGNORS TO THE FIRMA FABRIK FÜR SPEZIALNÄHMASCHINEN, ACTIEN-GESELLSCHAFT, (PATENTE, JULIUS GUTMANN,) OF ZURICH, SWITZERLAND.

BUTTONHOLE-SEWING MACHINE.

SPECIFICATION forming part of Letters Patent No. 634,134, dated October 3, 1899.

Original application filed August 31, 1897, Serial No. 650,162. Divided and this application filed October 3, 1898. Serial No. 692,529. (No model.)

To all whom it may concern:

Be it known that we, JULIUS GUTMANN, residing at Berlin, Germany, and EMIL FALLER and KARL MISCHKE, residing at Zurich, Switzerland, have invented certain new and useful Improvements in Buttonhole-Sewing Machines; and we do hereby declare the following to be a full, clear, and exact description of the invention, such as will enable others skilled in the art to which it appertains to make and use the same.

This invention has relation to that type of buttonhole-sewing machine shown and described in our application for Letters Patent of the United States filed August 31, 1897, Serial No. 650,162, of which application the present one is a division or continuation, and has relation to the mechanism which operates the work-holder and its application to a sewing-machine the needle-bar of which receives a vertical reciprocating motion only instead of such a motion and a vibrating motion, and particularly in the application of said mechanism to the well-known Wheeler & Wilson buttonhole-sewing machine, and whereby the edges of a buttonhole are bound in the usual manner, while its ends are barred by stitches laid parallel to said edges or substantially so.

In the accompanying drawings, Figure 1 is a side elevation, and Fig. 2 a top plan view, (the overhanging machine-arm being removed,) of a Wheeler & Wilson buttonhole-sewing machine provided with our improved mechanism for imparting to the work-holder the movements necessary to the binding of the edges and barring the ends of buttonholes. Fig. 3 is a view similar to Fig. 2, the feed-wheel and other parts being removed. Fig. 4 is a vertical longitudinal section taken on or about on line $z z$ of Fig. 3. Fig. 5 is a detail side elevation of that portion of the work-holder-actuating mechanism located above the bed-plate of the machine. Fig. 6 is a detail plan view of the actuating ring or collar for the feed-wheel. Figs. 7, 8, and 9 are detail top and bottom plan views and a side elevation, respectively, of the disks O and O', illustrating their construction and the means

for coupling the same together so as to permit disk O' to reciprocate on disk O when uncoupled therefrom. Figs. 10 and 12 are detail top plan views of the system of slides, parts being removed in said Fig. 12. Fig. 11 is a section taken on or about on line $w w$ of Fig. 10. Fig. 13 is a detail vertical section taken on or about on line $x x$ of said Fig. 10. Fig. 14 is a detail plan view, and Fig. 15 is a section on line $y y$ of Fig. 14. Fig. 16 is an under side view of the bed-plate, showing the connecting rod or bar m^4 coupled with the mechanism which imparts reciprocating motion to the work-holder during the barring operation. Fig. 17 is a view similar to Fig. 16, some of the mechanism being removed, showing the aforesaid rod coupled with the slide s^2 of a system of slides S, connected with the work-holder and adapted to reciprocate the same during the binding operation; and Fig. 18 is a section on line $v v$ of Fig. 17.

As clearly shown in Fig. 2, the work-holder, consisting of a transversely-slotted work-support P and a correspondingly-slotted cloth-clamp and stretcher-plate K, of well-known construction and hereinafter referred to as the work-holder PK, is arranged to hold the work with the buttonhole transversely of the bed-plate. The said work-holder is connected with a disk O', provided in its under face with a cam or heart-shaped groove o' , Figs. 4 and 8, through a system of slides S, and said disk O' is coupled to a disk O on a feed-wheel Q in such manner as to have reciprocating motion on said disk O when uncoupled therefrom. The connection between the parts is also such as to actuate the work-holder as follows: Supposing the parts to be in the position shown in Fig. 2 and the needle N to lie close to the right-hand edge above the near end of the buttonhole to commence the binding of said edge, as the needle N is reciprocated vertically the work-holder P K receives a reciprocating motion crosswise of the buttonhole, arrow I, Fig. 2, and simultaneously therewith a progressive feed motion in the direction of the right-hand arrow of the two arrows II through the left-hand portion

1 1 of the cam-groove o' in cam O' , Fig. 8, thereby forming the zigzag binding-strokes. As the work-holder $P K$ reaches the limit of its progressive feed motion—*i.e.*, the opposite 5 end of the buttonhole—the said work-holder will be uncoupled from the system of slides and coupled to a system of levers adapted to reciprocate the work-holder lengthwise of the buttonhole, arrow III , Fig. 2, and simultaneously therewith said work-holder will receive a progressive feed motion crosswise of the buttonhole or in the direction of the lower one of the two arrows IV , Fig. 2, whereby the off end of the buttonhole is barred by stitches 10 laid parallel with its edges or substantially so. During the barring operation the pin p' , Fig. 11, that works in the cam-groove o' in disk O' will lie in the concentric portion 1 3, as indicated at 2, Fig. 8, while the said disk 15 O' , is uncoupled from disk O and is reciprocated by the pin. When the off end of the buttonhole is barred, the parts are automatically returned into their first position for the binding of the opposite or left-hand edge of the buttonhole, during which operation the work-holder $P K$ is again reciprocated in the direction of arrow I , Fig. 2, while the direction of its progressive feed motion is reversed 20 by the other portion of the cam-groove o' in disk O' and indicated by the left-hand arrow of the two arrows II , Fig. 2. When said left-hand edge of the buttonhole is bound, the mechanism is again moved to actuate the work-holder $P K$ to bar the near end of the 25 buttonhole, during which operation said work-holder will again be reciprocated in the direction of arrow III , Fig. 2, and receive a progressive feed motion in the direction of the upper one of the two arrows IV , and when 30 said end is barred the work-holder will again be in the position of starting.

The stitch-forming devices are in construction and operation the same as those of the Wheeler & Wilson machine referred to, and 35 need therefore not be described in detail, while the reciprocating movements crosswise and lengthwise of the buttonhole are imparted to the work-holder, as hereinafter described, from a well-known switch-cam M on the lower machine-shaft w^3 and the continuously-vibrated lever M^2 , the arm m' of which carries a pin that projects into the groove of said switch-cam M .

As stated above, the work-holder $P K$ receives its feed motion in binding a buttonhole edge from the cam-groove o' in a disk O' , in which groove works a pin p' , that carries a roller and is secured to a slide p , Figs. 10 and 11. The slide p has a guide-block p^2 , journaled to its under side, which works in a diagonal groove p^3 in a slide p^4 , itself provided with a like guide-block that works in a groove p^6 of a slide p^7 , which is guided in a slide s' , which slide s' and the lower slide s^2 , guided 60 in suitable ways on the bed-plate G' , have motion independently of each other as well as together under the action of two springs $t^1 t^4$, seated in recesses in slide s^2 . The described arrangement of slides $s' s^2$ relatively to each other and relatively to the slides $p p^4 p^7$ and their construction being well known and used on the Wheeler & Wilson machines will hereinafter be referred to as the system of slides S , the work-support P being connected to slide s' through slide p^7 , to which said work-holder is rigidly secured, as shown in Figs. 4 and 11.

The reciprocating motion in the direction of arrow I , Fig. 2, in binding is imparted to the work-holder $P K$ by a connecting rod or bar m^4 , adjustably held in a longitudinal slot in the arm m' of the aforementioned switch-cam lever M , said bar m^4 having at its free end a square pin or stud that projects from its opposite faces and an offset or projection m^{4x} on its under side. The portion m^5 of the aforesaid pin takes into a slot m^6 in a projection or shoulder on the under side of the slide s^2 of the system of slides S , which is thus reciprocated in the direction of arrow I , Fig. 2, whereby and through the slide s^2 of said system of slides the work-holder $P K$ is similarly reciprocated, the bar m^4 being held in engagement with the slide s^2 by a spring f , Figs. 17 and 18.

The simultaneous progressive feed motion in the direction of one of the arrows II , Fig. 2, necessary to the formation of the binding-strokes and the binding of a buttonhole edge is imparted to the work-holder $P K$ by one or the other portion 1 1 or 3 3 of the cam-groove o' in disk O' through the slide p of the system of slides S , as hereinabove stated. The disk O' is rotated progressively by a disk O , which, as stated above, is coupled to disk O' and, through a ratchet-toothed feed-wheel Q , secured to disk O . The feed-wheel Q receives a progressive rotation from a pawl Q' , pivoted to an actuating ring or collar q' and held in engagement with the teeth on the feed-wheel by a spring q , said collar being free to oscillate on disk O , and is connected by a connecting-rod q^2 with the arm m^2 of the switch-cam lever M^2 , Fig. 2, said rod being likewise adjustable in a longitudinal slot in said arm m^2 of lever M^2 , for purposes well understood, the usual auxiliary pawl, Fig. 2, being provided to prevent backward rotation of the feed-wheel. When the work-holder has reached the limit of its progressive feed motion in the direction of one or the other of the two arrows II , Fig. 2, the pin p' on slide p is about to enter one of the concentric portions 1 3 of the cam-groove o' in disk O' , at which time the system of slides is uncoupled from the vibrating lever M^2 and then coupled to the work-holder. The vibrating lever M^2 is uncoupled from slide s^2 and coupled to mechanism adapted to reciprocate the work-holder in the direction of arrow III , Fig. 2, as follows: The aforementioned disk O has two peripheral projections t^9 diametrically opposite each other, and the disk O is provided with two similar projections t , Figs. 4, 7, 8, and 9, and

when one edge of a buttonhole is bound one of said projections l^0 will impinge upon a lever l , Figs. 2 and 3, secured to a pin l^2 revolvable in an arm l' , secured to a slide s' . The 5 said pin of lever l carries below the bed-plate G a shifting lever l^3 , the free end of which carries a roller l^4 in contact with the ledge or projection m^{4X} of connecting-bar m^4 , Fig. 16, so that as said lever l is moved outward by 10 the projection l^0 the lever l^3 will move the bar m^4 against the stress of its spring f , so as to disengage the portion m^5 of its square lug or pin from the slot m^6 in the projection on the under side of slide s^2 and move the portion n^5 15 of said pin on the opposite side of said bar m^4 into a notch n^6 in a link n^4 . One end of this link is pivoted to one end of a link n^8 , whose opposite end is pivoted to the under side of the bed-plate G' . The other end of link n^4 is 20 pivoted to the arm n^7 of a bell-crank lever N^7 , likewise fulcrumed to the under side of the bed-plate. The arm n^{17} of bell-crank lever N^7 has at its free end a stud or pin n^8 , that extends through a slot in and formed trans- 25 versely of the bed-plate, and has secured thereto above said bed-plate a slide r .

From what has been said above it will readily be seen that the vibration of the lever M^2 will be transmitted through the connecting-bar m^4 to the link n^4 , which latter will receive a reciprocating motion lengthwise of the bed-plate, which motion is transmitted to the slide r through the bell-crank lever N^7 , so as to reciprocate said slide transversely of 35 said bed-plate, arrow III, Fig. 2. In order that this reciprocal motion of the slide r may be transmitted to the work-holder $P K$, they are automatically coupled together as follows, reference being had to Figs. 3, 4, 10, 12, 40 and 13.

The slide r carries a spring-actuated lever r' , the spring f' of which tends to force said lever toward the slide r or downward. The lever r' extends through a sleeve r^0 , secured 45 to the slide, in which sleeve is guided a coupling-pin r^2 , pivoted to lever r' , which pin under the stress of spring f' on lever r' is forced downward through a suitable opening in slide r , Fig. 4. To the work-support P is secured a transversely-slotted plate q^6 , to which are adjustably secured two longitudinally-slotted coupling-plates $q^4 q^5$ by means of set-screws q^8 , passing through a transverse slot q^7 in said plates, so that the said coupling-plates 55 can be adjusted to the length of buttonhole to be bound and barred. To prevent accidental displacement of the coupling-plates $q^4 q^5$ on their screws q^8 when the work-holder is reciprocated, the slotted body of said plates is made 60 thicker than their shanks, and said thicker portion projects into the transverse slot q^{6X} in plate q^6 , as shown in Fig. 13. When the work-holder $P K$ has reached the limit of its progressive feed motion in the direction of one or 65 the other of the two arrows II, Fig. 2, the slot in one or the other of the coupling-plates q^4 or q^5 will lie immediately under the coupling-pin

r^2 , which is moved into the same by the action of spring f on lever r' , as above stated. The outer or off end of the slide r is guided 70 by a pin n^{10} , projecting from the bed-plate G' through a longitudinal slot n^9 in said slide, of sufficient length to admit of the required short reciprocations of said slide necessary to the formation of the barring-stitches. During 75 the operation of binding the edges of a buttonhole it is of course necessary that the slide r should be uncoupled from the work-holder $P K$ to allow the same to reciprocate in a direction at right angles to said slide, arrow I, 80 Fig. 2. To this end the lever r' has at its outer end a pin r^3 , bent at right angles and acted upon by a radial arm r^4 on a spindle r^5 , on which is mounted a torsion-spring f^2 , that tends to turn the said spindle so that the 85 arm r^4 will lift the pin r^3 and lever r' against the stress of its spring f' and hold the coupling-pin r^2 out of the path of the coupling-plates $q^4 q^5$. The spindle r^5 has a second radial arm or pin r^6 , that is held in contact with 90 a pawl r^7 , adjustable lengthwise on said spindle through the medium of a block 20, Fig. 2, pivoted to a suitable support 21, Fig. 5, in which said spindle is journaled, said block lying in a longitudinal slot 22 of said pawl, 95 which is secured in its adjusted position by means of a set-screw 23. By the means described the coupling-pin r^2 on lever r' is held out of the path of the coupling-plates $q^4 q^5$ on work-holder $P K$. 100

In order that the lever r' may be automatically released at the proper time and its coupling-pin moved into engagement with one or the other of the two coupling-plates $q^4 q^5$ —that is to say, at the time when the bar m^4 is uncoupled from slides s^2 and coupled to link n^4 , as above described—the pawl r^7 is held by the block 20 in the path of the projections l^0 on disk O , above referred to, so that as one of these projections acts upon lever l to uncouple the connecting-bar from slide s^2 of the system of slides S and couple the same with the link n^4 of the appliances that impart reciprocating motion to slide r the other projection l^0 acts upon pawl r^7 and the latter 110 upon the radial arm r^6 to turn the spindle r^5 against the stress of its torsion-spring f^2 , thereby allowing spring f' of lever r' to force the same down and its pin into the slot q^3 of the coupling-plate q^4 or q^5 lying at the time 115 below said pin. The projections l^0 have of course such a peripheral length as to admit of the required number of barring-stitches being formed to bar a buttonhole end. 120

As hereinbefore stated, during the barring 125 of a buttonhole end the pin and roller p' on slide p of the system of slides S lies in one or the other of the concentric portions 13 of the cam-groove o' in disk O' , and to which pin p' the reciprocating motion of the work-holder 130 $P K$ is transmitted, so that it is necessary that said disk O' should be so connected with the disk O , actuated by the feed-wheel Q , as to partake of said reciprocations of the work-

holder. The appliances whereby said disk O' is coupled to disk O, so as to permit it to reciprocate with the work-holder, are fully described and shown in our application for 5 patent first herein referred to and will need, therefore, but a brief description here, reference being had to Figs. 7 and 8.

The disk O', provided with the cam-groove o', is connected with the disk O by means of 10 guide-rails o⁶, having sliding motion in suitable slots in the disk O, Fig. 7. o² o³ indicate the spring-actuated coupling-latches, pivoted in suitable recesses in the under side of the disk O and working in suitable recesses 15 in the upper face of disk O', the springs o⁵ for said latches o² o³ tending to throw the same outwardly. The coupling-latches are each provided with a substantially square opening o⁷, having in its inner wall a recess 4, into 20 which projects a stud o⁴ on the upper face of disk O', the opening o⁷ in the latches being of such diameter as to permit the required reciprocation of disk O' when the latches are uncoupled from the pins o⁴. This uncoupling 25 is effected in that the latches when coupled to the studs o⁴ project beyond the periphery of the disks O and O' in the path of two rollers A' and o⁸, Fig. 3, on pins secured to the bed-plate G' and to a bracket o⁹, Fig. 4, secured 30 to a disk p⁰, that supports the disks O' O and feed-wheel Q.

The arrangement of the roller-abutments and coupling-latches relatively to the peripheral projections l⁰ on disk O is such that the 35 moment the lever M² is coupled with the link n⁴ and the pawl n⁷ acts upon spindle r⁵ to release the lever r', and thereby bring its coupling-pin into engagement with the slot in one or the other of the coupling-plates q⁴ q⁵, the said 40 rollers A' and o⁸ will move the coupling-latches o² o³ inwardly, thereby moving the recesses 4 in the inner edge of the openings in said latches out of engagement with the studs o⁴ on disk O' and permit the latter to partake of the reciprocating motion of slide r and work-holder 45 P K in the direction of arrow III, Fig. 2, during the barring operations.

The progressive feed motion in the direction of one or the other of the two arrows IV, 50 Fig. 2, necessary to the barring of a button-hole end is imparted to the work-holder P K by the aforementioned cam projections t on the periphery of disk O, Figs. 3, 7, and 8, acting upon a roller t' on a pin t², projecting 55 through an oblong slot in the upper slide s' and rigidly secured to the lower slide s² of the system of slides S, Figs. 3 and 4, the said slides s' s² being connected to move together, as hereinbefore described, by the springs t⁴ t¹, 60 Figs. 4, 12, 14, and 15. In the pin or post t² works an adjusting-screw t⁶, that abuts against the fixed disk p⁰, which supports the disks O' O and feed-wheel Q, whereby the roller t' on said pin or post t² is held in proper position relatively to the peripheral cam projections t on said disk O, as shown in Fig. 4.

Having thus described our invention, what

we claim as new therein, and desire to secure by Letters Patent, is—

1. In a buttonhole-sewing machine such as 70 described, the combination with the stitch-forming appliances, the work-holder, the switch-cam M, the switch-cam lever M², mechanism operated by said lever and adapted to impart to the work-holder a reciprocating motion crosswise of the buttonhole, and mechanism adapted to simultaneously impart to said work-holder a progressive feed motion lengthwise of the buttonhole whereby one edge of a buttonhole is bound, of a slide adapted to 80 be coupled to the work-holder, mechanism operated by the aforesaid switch-cam lever and adapted to impart to said slide a reciprocating motion lengthwise of the buttonhole, mechanism adapted to simultaneously impart to said work-holder a progressive feed motion crosswise of the buttonhole a lever adapted to uncouple the switch-cam lever from the mechanism which imparts to the work-holder a reciprocating motion lengthwise of the buttonhole when said work-holder reaches the limit of its progressive feed motion in the same direction and couple the same to the aforesaid slide, and means adapted to simultaneously couple said slide to said work-holder whereby one end of a buttonhole is 90 barred by stitches laid substantially parallel with its edges, substantially as set forth.

2. In a buttonhole-sewing machine such as 100 described, the combination with the stitch-forming appliances, the work-holder, the switch-cam M, the switch-cam lever M², mechanism operated by said lever and adapted to impart to the work-holder a reciprocating motion crosswise of the buttonhole, and mechanism adapted to simultaneously impart to 105 said work-holder a progressive feed motion lengthwise of the buttonhole whereby one edge of a buttonhole is bound, of a slide adapted to be coupled to the work-holder, mechanism operated by the aforesaid switch-cam lever and adapted to impart to said slide a reciprocating motion lengthwise of the button-hole, mechanism adapted to simultaneously impart to said work-holder a progressive feed motion 110 crosswise of the buttonhole a lever adapted to uncouple the switch-cam lever from the mechanism which imparts to the work-holder a reciprocating motion lengthwise of the buttonhole when said work-holder reaches the limit of its progressive feed motion in the same direction and couple the same to the aforesaid slide, means adapted to simultaneously couple said slide to said work-holder whereby one end of a buttonhole is 115 barred by stitches laid substantially parallel with its edges, and appliances organized to repeat the above-described operations, for the purpose set forth.

3. The combination with the stitch-forming 120 appliances, the work-holder and the system of slides S, said work-holder secured to the slide p⁷ of said system, and means for imparting to said work-holder a progressive feed mo-

tion lengthwise of the buttonhole; of the switch-cam M, the lever M², the connecting-bar m⁴ provided with a lug engaging a slot m⁶ in a projection on the under side of slide s² of the aforesaid system of slides S, whereby the work-holder is reciprocated crosswise of the button-hole, and the spring f for maintaining the engagement of the said lug on bar m⁴ with said slot m⁶, substantially as and for the purpose set forth.

4. The combination with the slides p⁷ s² of the system of slides S, the work-holder P K secured to slide p⁷, the switch-cam M, the lever M² vibrated thereby and the spring-controlled bar m⁴ connected with said lever and provided with a pin projecting from opposite faces at its free end, one portion m⁶ of said pin in engagement with a slot m⁵ in a projection on the aforesaid slide s², the slide r adapted to be coupled to the work-holder, the bell-crank lever N⁷ whose arm n¹⁷ is connected with said slide r, the link n⁸, the link n⁴ connecting said link n⁸ with the other arm n⁷ of said bell-crank lever and having a notch n⁶, of a shifting-lever adapted to shift the connecting-bar m⁴ against the stress of its spring to move the part m⁶ of its pin out of the slot m⁵ of slide s² and move the part n⁵ of said pin into the notch n⁶ of link n⁴, substantially as and for the purpose set forth.

5. The combination with the stitch-forming appliances, the switch-cam M, switch-cam lever M², the work-holder, and mechanism operated by said lever to impart to the work-holder a reciprocating motion crosswise of the buttonhole, of the feed-wheel Q, the disk O secured thereto, the disk O' connected with the disk O and provided with the cam-groove o' in its under face, the slide p of the system of slides S connected with the work-holder, said slide p having a pin p' that projects into the aforesaid cam-groove, the ring q' connected with one of the arms of the aforesaid switch-cam lever and the pawl Q' pivoted to said ring q' and engaging the teeth of the feed-wheel Q, substantially as and for the purposes set forth.

6. The combination with the stitch-forming appliances, the switch-cam M, the switch-cam lever M², the work-holder, the slide r, intermediate mechanism connecting said slide with said switch-cam lever and adapted to impart to the slide a reciprocating motion lengthwise of the buttonhole, and means for coupling said slide to the work-holder, of the feed-wheel Q, mechanism operated by the switch-cam lever and adapted to impart to said feed-wheel a progressive rotation, the disk O secured to the feed-wheel, the disk O' coupled to said disk O, and means for uncoupling the same automatically when the slide r is being coupled to the work-holder, said disk O' having the cam-groove o' in its under face, the slide p of the system of slides S connected with the work-holder, said slide p having a pin p' projecting into the aforesaid cam-groove, and means for imparting to the work-holder a progressive feed motion crosswise

of the buttonhole, substantially as and for the purpose set forth.

7. The combination with the work-holder, 70 the plate q⁶ secured thereto and the coupling-plates q⁴ q⁵ connected with plate q⁶, the slide r carrying the spring-depressed lever r' and the pin r² pivoted to said lever and adapted to engage one or the other of the two coupling-plates q⁴ q⁵, said lever r' having an angular pin or arm r³ at its free end, the spindle r⁵, the torsion-spring f² thereon, said spindle provided with a radial arm r⁴ in engagement with the pin r³ and tending to lift lever r' against the stress of its spring under the action of the torsion-spring on spindle r⁵, and a second radial arm r⁶ on said spindle; of the feed-wheel Q, the disk O secured thereto and provided with the peripheral projections 85 70 and the pawl r⁷ in the path of said projections and adapted to act upon the radial arm r⁶ to turn the spindle r⁵ against the stress of its torsion-spring, substantially as and for the purposes set forth.

8. The combination with the stitch-forming appliances, the work-holder, the mechanism for imparting to said work-holder a progressive feed motion lengthwise of the buttonhole and a reciprocating motion crosswise thereof, 95 comprising a progressively-revolving feed-wheel having a cam-groove in its under side the system of slides S connecting said cam-groove with the work-holder, the reciprocating coupling-bar m⁴ coupled to the work-holder through one of the slides of said system, means for imparting to one of said slides a progressive motion crosswise of the button-hole, and mechanism for reciprocating the work-holder lengthwise of the buttonhole; 100 of the disk O revolving with the feed-wheel and having peripheral projections l⁰, the lever l in the path of said projections, the shifting-lever l' on the fulcrum of lever l and acting on the bar m⁴ to uncouple the same from the system of slides and couple it to the mechanism for reciprocating the work-holder lengthwise of the buttonhole, substantially as and for the purpose set forth.

9. The combination with the stitch-forming devices, the work-holder, the switch-cam M, switch-cam lever M², the slide r and mechanism operated by said switch-cam lever and adapted to impart to the slide r a reciprocating motion lengthwise of the buttonhole, and means for coupling the slide to the work-holder, of the feed-wheel Q operated from the aforesaid switch-cam lever, the disk O secured to said feed-wheel and provided with the peripheral cam projections t, the disk O' provided with the cam-grooves o' in its under face, said disk O' coupled to disk O, means for uncoupling the said disks when slide r is being coupled to the work-holder, the slide p provided with a pin p' projecting into the cam-groove 125 of disk O', the slide p⁷ to which the work-holder is secured, the slide p⁴ connecting slides p and p⁷, the slide s' connected with slide p⁷, the slide s² connected with slide s' and the

post l^2 carrying a roller l' in the path of the cam projection l on disk O, substantially as and for the purposes set forth.

10. The combination with the stitch-forming appliances, the work-holder and the system of slides S, said work-holder secured to the slide p^7 of said system, and means for imparting to said work-holder a progressive feed motion lengthwise of the buttonhole; of the switch-cam M, the lever M^2 , the connecting-bar m^4 provided with a lug engaging a slot m^6 in a projection on the under side of slide s^2 of the aforesaid system of slides S, whereby the work-holder is reciprocated crosswise of the buttonhole, the spring f for maintaining the engagement of the said lug on bar m^4 with said slot m^6 , and means for disengaging the lug from said slot, substantially as and for the purpose set forth.
20. 11. In a buttonhole-sewing machine, the combination with the work-holder, a progressively-revolving feed-wheel, a cam-grooved feed-disk revolving with and reciprocating on said feed-wheel, means for locking the disk against reciprocation, a connection between the work-holder and the cam-groove in said disk, and means for periodically imparting to said work-holder a progressive motion crosswise of the bed-plate and a reciprocating motion lengthwise thereof; of mechanism for unlocking the disk from the feed-wheel when the

work-holder is reciprocated and moved progressively, as described, for the purpose set forth.

12. In a buttonhole-sewing machine, mechanism for barring the end of a buttonhole, comprising the vertically-reciprocating needle-bar, the work-holder, and mechanism for reciprocating and simultaneously imparting to said work-holder a progressive motion at 40 right angles to the direction of its reciprocation, said mechanism including a two-part cam-grooved progressively-revolving feed-wheel, one of said parts capable of reciprocating on the other and said work-holder connected with the cam-groove for the purpose set forth.

In testimony that we claim the foregoing as our invention we have hereto signed our names in presence of the subscribing witnesses.

JULIUS GUTMANN.
EMIL FALLER.
KARL MISCHKE.
